UNITED STATES PATENT OFFICE.

EDGAR A. EDWARDS, OF CINCINNATI, ASSIGNOR TO O. M. GOTTSCHALL,
TRUSTEE, OF DAYTON, OHIO.

ELECTRIC-ARC LAMP.

SPECIFICATION forming part of Letters Patent No. 275,170, dated April 3, 1883.

Application filed October 17, 1882. (No model.)

To all whom it may concern:

Be it known that I, EDGAR A. EDWARDS, a citizen of the United States, and a resident of Cincinnati, in the county of Hamilton and State of Ohio, have invented certain new and useful Improvements in Electric Lights, of which the following is a specification.

My invention relates to improvements in electric-light regulators, or mechanism for the adjustment of carbons in electric lamps of the arc type, and particularly to that class of lamps in which two or more sets of carbons are successively burned, so that the length of time that a lamp will work without renewing the carbons is multiplied by the number of sets of carbons employed. This is effected by having strong operating electro-magnets actuating separate and independent mechanisms for adjusting each respective carbon-rod. The connections are made so that the several sets of carbons are placed in multiple arc.

The various features of my invention will be fully set forth in the following description of the accompanying drawings, of which—

Figure 1 is a broken perspective with one pair of helices removed; Fig. 2, an elevation of the lamp with the case in section, showing the mechanism of one side, the mechanism of the other side being exactly similar; Fig. 3, a sectional plan on line *x* *x*, Fig. 2; Fig. 4, a detail view of the lower yoke; Fig. 5, a section of the core of one of the magnets. Fig. 6 is a plan view of the carbon-rod clutch. Fig. 7 is a perspective in broken section, showing connection of pendulous armature to polar yoke of magnets.

I have shown my lamp with two sets of carbon-rods and their respective adjusting mechanisms, each of which mechanisms is a duplicate of the other.

I do not limit the application of my invention to two sets of adjusting mechanisms, as any desired number may be employed.

The letters indicating the various parts which are duplicated are marked with a prime (') to indicate the duplicate upon the opposite side.

A represents a metal case; *B* *B'*, helices of the principle magnet.

50 *B''* and *B'''* represent the helices of the shunt-magnet; *CC'*, maximum magnetic yokes.

Each of these yokes is provided with downwardly-projecting lugs *dd'*, forming maximum polar points for magnetically charging the pendulous armatures *E*, which are suspended by flexible metallic strips or pivotal bearings.

In order to prevent a tendency to attract the armature from its vertical line of movement, I provide two lugs, *d d'*, mentioned above, one upon each side of the armature.

F F' represent arms secured rigidly to their respective armatures and projecting outwardly over the carbon-rods.

G represents a connecting-rod attached at one end to crank-arm *F*, either by flexible spring or pivot, and connected at the other end with the lever *H*, which carries the clutch *h*, (see Fig. 6,) to operate the carbon-rod *J*. This connection is made by means of a stirrup or other jointed connection, which allows the requisite pitman movement. The clutch *h* is similar in construction to the clutch described in my application for patent for electric light, filed simultaneously with the present application. It is a three-point clutch embracing the carbon-rod *J*, as shown. When the lever *H* rises, the clutch is elevated at one side, and the carbon-rod is crimped between its points and lifted; but when the lever descends, the clutch slips on the rod.

i represents a dash-pot plunger-rod, rigidly secured to rod *G* and operating in dash-pot *I*.

e represents a maximum polar point on the bottom yoke. This polar point is placed in such relation to the pendulous armature *E* that the latter will, when attracted, swing freely over it.

s represents a retractile spring, one end of which is attached to the armature, the other end of which is attached to the case *A*, which is provided with the usual means for regulating its tension.

M represents the tubular core of the magnets, through which pass the carbon-rods *J*, which should be made of brass or other non-magnetic material. This arrangement is made for the purpose of economizing space in the lamp-case.

The principal and shunt magnets are so wound and connected as to induce their opposite magnetisms into the same yoke, viz.: If the principal magnet coils should induce positive mag-

netism in the top yoke and negative magnetism in the bottom, the shunt-magnet will induce its negative magnetism in the top yoke and its positive magnetism in the bottom yoke.

5 The operation of my lamp is as follows, the drawings representing the parts in the positions they occupy before the current is passed through the lamp: When the current is sent through the lamp the attraction of both the 10 armatures toward their respective lugs e e' is the same; but, owing to the slightly greater resistance of the retractile spring s' , armature E will move toward the upwardly-projecting lug e after the other, thus elevating the end of 15 arm F and carrying upward the link-and-clutch mechanism, thus causing the clutch to engage with the carbon-rod, causing it, with its carbon, to move upward, thus effecting the initial separation of one pair of carbons. The 20 relative retractile-spring adjustments of the two mechanisms are such that one armature—say E' —begins to move toward polar point e' , thereby elevating end of arm F' and raising the rod-and-clutch mechanism G' H' before 25 the other armature will have moved, in which case the longest initial separation takes place between the pair of carbons the upper one of which is carried by the rod J' . Now, since the current is divided, passing through the 30 two pairs of carbons, the arc will break, or the current will cease to flow between the pair sustaining the longest separation, thus throwing the whole of the current between the second pair of carbons and maintaining the arc.

35 On the lengthening of the arc by disintegration of the carbon, thus causing a neutralization of the magnetism by reason of the greater excitation of helices B'' B''' , the armature E' , with its connecting mechanism, clutch, and 40 rod, will be the first to be affected. Armature E does not move toward its first position until armature E' shall have partly returned to its first position and caused the feeding of its carbon-rod by the tripping of clutch-lever 45 H' on the floor of case A . The result is that the carbon connected with rod J' will be wholly consumed, and projection L' on the top of rod J will rest on the bearing K' and stop its downward movement, when, owing to the considerable length of arc resulting, so much current 50 is shunted through the differential helices B'' B''' that a total magnetic neutralization takes place, so that the weaker retractile spring, s , draws armature E so far toward its first position 55 that the clutch connected with rod J is tripped, slides through, and its carbon makes contact with its lower carbon, establishing an arc of lower resistance than that between carbon O of rod J and carbon O' , when the arc between 60 carbons O O' is instantly broken.

It is evident that should the downward movement of the upper one of the last separated pair of carbons be stopped from any cause its arc will be broken and the second pair of car-

bons ignited the same as though the first pair had been burned out.

Q indicates a crank for switching the carbons in and out of circuit, pivoted upon extension Q' , which is insulated from contact-point v , so that when crank Q is in contact with lug v the circuit through the carbons is broken. It will also be seen that there are peculiar advantages in this form of multiple-carbon lamp over those forms in which one set of mechanism actuates both sets of carbons, as in that case if the mechanism becomes deranged it affects both sets of carbons and the light is extinguished, whereas in my improved device each carbon-rod has separate and independent mechanism, and should one set become broken or disarranged the other carbon-rod is not affected.

It is evident that the magnets, armatures, clutch mechanism, and carbon-holders might be duplicated in the same case, so as to form a series of more than two carbons, each armature having a different retractile-spring adjustment.

I claim—

1. In an electric lamp, the combination of a series of sets of carbons connected in multiple-arc circuit, differential electro-magnets, and two or more armatures, each operating independent carbon-regulating devices, and each of said armatures having a different relative retractile adjustment, substantially as described.

2. In an electric lamp, the combination of a series of sets of carbons connected in multiple-arc circuit, differential electro-magnets, and two or more armatures, each operating independent carbon-adjusting mechanism actuated by said electro-magnets and relatively adjusted to each other, so as to produce successive carbon separation, substantially as described.

3. In an electric-arc lamp designed to operate two or more sets of carbons, the shunt electro-magnet having helices B'' B''' , connected in derivation of the arc and principal electro-magnets, having yokes C C' , in combination with the vertical horizontally-moving armatures E E' , having arms F F' , links G G' , and clutch-levers H H' , arranged to operate the carbon-rods J J' , substantially as described.

4. The combination, with the independently-movable armatures, separate carbon-lifting devices, and single electro-magnet, of the springs s s' , arranged to retract said armatures, respectively, with different degrees of force, substantially as and for the purpose set forth.

In testimony whereof I have hereunto set my hand in the presence of two subscribing witnesses.

EDGAR A. EDWARDS.
